INVENTOR

BY *Harold Dodd*
ATTORNEY

UNITED STATES PATENT OFFICE

EMORY A. BRYANT, OF WASHINGTON, DISTRICT OF COLUMBIA

FRACTURE APPLIANCE

Application filed November 14, 1929. Serial No. 407,088.

(GRANTED UNDER THE ACT OF MARCH 3, 1883, AS AMENDED APRIL 30, 1928; 370 O. G. 757)

My invention relates broadly to a fracture appliance and bandage for fractures, and more particularly to the bandaging and re-tension of fractures of the maxillary bones 5 of the face in proper position during the period of healing and restoration to normal function, while at the same time retaining the normal action of the inferior maxillary in the process of feeding, drinking and speaking, opening and closing the mouth.

The object of my invention is to retain the fractured parts of the superior or inferior maxillary bones in proper apposition by means of an appliance and bandage applied 15 externally to the face and jaws, while at the same time allowing the patient to take nourishment, drink, and to converse in comfort without displacement of the fragments or the fractured parts, and to avoid the danger of 20 death by suffocation of patients being at sea and subjected to sea-sickness, caused by inability to open the mouth and expell the vomit where the bandaging or wiring of the teeth in an immobile position has heretofore been 25 resorted to, and serious results occurred.

With the above objects in view, my invention consists in the construction, combination and arrangement of parts as will be described more fully hereinafter.

Reference is to be had to the accompanying drawings forming a part of this specification, in which like reference characters indicate corresponding parts throughout the several views, and in which:

Figure 1 is an elevation of one side of my improved device as applied to a patient;

Figure 2 is a side view of my invention as applied with bandages to the face of a patient;

Figure 3 is a back view of my improved device as applied with bandages to a patient.

Referring more particularly to the drawings, 10 indicates a head piece or wire to which are hinged by screw posts 11 and screws 12, brace extension wires 13. Adjusting units 14 are positioned on the head piece 10 by set screws 15. Removably secured to wires 13 by set screws 16 are brace tubes or sleeves 17 that have positioned in their ends a jaw brace or cup wire 18. The cup wire 18 is

firmly held in the brace tubes 17 by set screws 19. A chin cup 20 that is adapted to fit up against and well in under the chin of a patient is placed on the wire 18 by means of a curved flange or lip 21 that is an integral part of the cup 20. The head piece 10 has rolls 22 suitably positioned thereon to act as pads when the piece is placed on the head and between the pads 22 is secured a supporting strip 23. The strip 23 is preferably of flexible metal so that the same can be curved around the contour of the head and turned up into a loop as at 24. In the posterior border of the cup 20 are apertures 25 through which fine wires 26 may be drawn in order to hold up the cup by fastening the wires 26 onto the sleeves 17 just in back of the screws 19.

In applying the appliance after the fractures have been reduced and temporarily held in place by any method indicated in the case 70 in hand, the tubes 17 and chin cup 20 are removed from the head wire 10 by unscrewing the hinge screw 12. The head wire is then placed with the rolls 22 on the head of the patient and the strip 23 turned over the head 75 wire 10 and secured to it, loop 24 at the neck being left open and turned down on the neck for the reception of a neck bandage 27 when applied. The hinge member 11 and screws 12 are now adjusted on the head wire 10 to 80 the point opposite the opening in the ear and one-half inch forward of the same, which is at the point of the tip of the condyle rest in the glenoid fossa. The unit 14 is then adjusted so that when the neck bandage 25 is 85 brought over it at the lower part of the lobe of the ear the bandage will not impinge upon the ear. Having adjusted the parts referred to, an assistant holds the head wire 10 in proper position on the head, a bandage of 90 suitable size is then passed round the chin and neck three or four times each turn over the unit 14 and spread out on the chin so as to cover the same. This bandage so far applied is then tied temporarily at the back of the 95 neck while the bandage is secured by tying the same to the head wire 10 at the adjusting unit 14. The hinge jaw brace 17 and the chin cup 20 are then taken and adjusted to the chin and jaw over the bandage already 100

in place until they rest properly and can be attached by the screws 16 to the head wire 10. Having set these two screws 16, the lip 21 of the cup 20 is placed over the jaw brace wire 18 and it is then wired through the holes 25 to the tube 17 just back of the screw adjustment 19 so that the chin cup 20 fits in place snugly to the chin.

Having made all the adjustments, four or 10 more turns of a bandage around the neck and chin cover all the metal parts from the point of the chin back on the jaw tube 17 going over the screw head 15 and under the ear lobes, tying as before and turning up and securing the 15 supporting strip by loop 24. The loose ends of the bandages are secured by a piece of tape and adhesive tape is used to secure and smooth out that portion of the bandage around the chin wire 18 thus making the 20 chin immovable except in opening and closing the mouth.

The appliance and bandage are now in place permanently until the proper time arrives, the fracture healed and the patient 25 ready to be discharged.

It will be understood that the above description and accompanying drawings comprehend only the general and preferred embodiment of my invention, and that various 30 changes in construction, proportion and arrangement of parts may be made within the scope of the appended claims, and without sacrificing any of the advantages of my invention.

35 The herein described invention may be manufactured and used by or for the Government of the United States for governmental purposes without the payment to me of any royalties thereon under provision of the act 40 of March 3, 1883 as amended April 30, 1928.

What I claim is:

1. In a fracture appliance and bandage for fractures of the maxillary bones, adjustable sleeves, a chin cup, means adjustably securing 45 said cup to the sleeves, a head piece extending over the head from points just below the ears, hinge means securing said sleeves to said head piece at a point corresponding with the junction of the condyles of mandible with the glenoid fossa, to allow horizontal motion to conform to the opening and closing of the mouth a bandage around all of said parts to hold the same in position and an adjustable unit on said head piece adapted to position and 50 to hold said bandage just below the lobes of the ears.

2. In a fracture appliance and bandage for fractures of the maxillary bones, a bandage extending around the chin, jaw and back 55 of the neck, a head piece extending over the head from points just below the ears, adjustable units on said head piece adapted to support said bandage just below the lobes of the ears, sleeves, hinge means detachably securing 60 said sleeves to each side of said head piece

70 at points on said piece to correspond with the junction of the condyles with the glenoid fossa, a jaw brace having its ends inserted into said sleeves, a chin cup placed on said brace and adapted to fit up in under and around the chin of a patient and a second bandage extending round said cup, jaw and back of the neck and also supported by said adjustable unit, whereby horizontal motion is allowed to conform with the opening and 75 closing of the mouth.

3. In a fracture appliance and bandage for fractures of the maxillary bones a bandage 80 extending around the chin, jaw and back of the neck, a head piece having pads thereon, extending from points just below the ears, adjustable units on each side of said piece adapted to support said bandage just below the lobes of the ears, sleeves, hinge means detachably securing said sleeves to each side of 85 said head piece at points on said piece corresponding to the junction of the condyles with the glenoid fossa, a jaw brace having its ends inserted into said sleeves, a chin cup placed on said brace and adapted to fit up in under and around the chin of a patient, means holding 90 said cup snugly under the chin, a second bandage extending round said cup, jaw and back of the neck and supported by said adjustable unit, and a supporting strip securing 95 to said head piece and following the contour of the back of the head to retain said head piece and bandages in proper position.
